UNITED STATES PATENT OFFICE.

MARIUS VERNAY, OF CORNILLON-BEAUJEU, FRANCE, ASSIGNOR TO ERNEST CADGÈNE, OF PATERSON, NEW JERSEY.

MACHINE FOR RUBBING TISSUES.

REISSUED

1,426,690.

Specification of Letters Patent. Patented Aug. 22, 1922.

Application filed September 2, 1921. Serial No. 497,943.

To all whom it may concern:

Be it known that I, MARIUS VERNAY, a citizen of the French Republic, and resident of Cornillon-Beaujeu, Department of Rhône, France, have invented certain new and useful Improvements in Machines for Rubbing Tissues, for which I have filed an application in France October 7, 1913, No. 473,709; Switzerland, December 24, 1918, No. 82,415; 10 and Austria, September 1, 1920, and of which the following is a specification.

After dyeing the silk fabrics are generally rubbed with a plug previously imbibed with a suitable liquid such as a solution of benzine, to take off the spots which appear on the tissue after dyeing, to equalize the tint, and to restore the brilliancy and softness of the silk. This operation is performed manually, and all attempts to realize it mechanically have hitherto failed.

The present invention has for its object the provision of a machine for the realization of this operation. Said machine is diagrammatically shown in the accompanying drawing, Fig. 1 in elevation and Fig. 2 in a plan view. Fig. 3 is a detail sectional view of the plug.

1 designates a rubbing member having reciprocating movement which it receives by 30 means of two connecting rods 2 and two crank shafts 3 keyed on a shaft 4 on which is also fixed a pulley 5 moved by a belt 6 and a suitable motor.

The member 1 is crossed by a pin 7 the 35 ends of which are connected to the connecting rods 2. Said plug consists of a wick of cotton or other suitable absorbent material surrounded by layers of cloth, felt, etc., constituting the rubbing surface. The upper 40 part of the plug is formed by a plate 9 having a number of holes receiving the tubulures of funnels 20 the lower part of which is immediately over the wick. At the centre of the plate 9 is a hand lever 10, and on opposite sides of said lever lead bars 21, 22 are 45 fixed to the plate 9.

The sectional view of the member 1 illustrates that such member is hollow and receives wicks 23 of cotton or other suitable material, surrounded by layers of cloth, felt or the like, 8. The upper part of the member is formed by a plate 9 fixed by screws 50 24, and having a number of holes 25 receiv-

ing the tubes of funnels 20, the lower ends of which are over the wicks 23.

The tissue is unrolled from a cylinder 11 and its tension is regulated by means of a weight 12. It passes on a table 13 where it is rubbed by the member 1, then on the rollers 14, 15, 16 and 17, on the table 18 where it is inspected, and finally is rolled on a cylinder 19.

The operation of the machine is as follows: The liquid employed for the treatment of the tissue is poured into the funnels 20 and saturates the wick, and by capillarity the cloth, felt or other rubbing material 8. When this latter is in a proper condition the machine is put in operation. The tissue unrolls from the cylinder 11 in the direction 65 indicated by the arrows Fig. 1, and the member 1 receives a reciprocating movement from the connecting rods 2 and the crank shafts 3. When the plug goes from the position indicated in full lines to that indicated in dotted lines it inclines to the right owing to the heavy lead bar 21, and when it returns in opposite direction, it inclines to the left owing to the lead bar 22 and the pulling action of the connecting rods 2. 70 75 80

It results that in its reciprocating movement the member 1 works on its whole rubbing surface in contact with the tissue which moves on the table 13, so that the wear of the member 1 is absolutely equal in its whole 85 surface. The lead bars also assure a convenient pressure of the said member to the tissue.

As the tissue passes on the table 18 it is examined by the attendant, and if necessary 90 it goes again to the machine for another treatment.

The run of the plug is regulated by fixing the trunnions of the connecting rods 2 in one or the other of the holes 3' of the crank 95 shaft 3.

It is to be understood that the reciprocating movement of the plug may be obtained by other means than that above described without departing from the spirit of the invention.

What I claim is:—

1. In machines for rubbing tissues the combination of a rubbing member having a wick surrounded by layers of absorbent material, a plate on the plug, funnels, the tubes 105

of which cross the plate and arranged over the wick, a table under the member, and means for giving to the tissue a longitudinal displacement over the table between the latter and the member.

2. In machines for rubbing tissues the combination of a rubbing member having a wick surrounded by layers of spongyous material, a plate on the said member, funnels, 10 the tubes of which cross the plate and arranged over the wick, a hand lever in the

centre of the plate, heavy lead bars on the plate on each side of the hand lever, a table under the said member, and means for giving to the tissue a longitudinal displacement 15 over the table between the latter and the said member.

In witness whereof I affix my signature.
MARIUS VERNAY.
